UNITED STATES PATENT OFFICE.

OSCAR SONDELM, OF NEW YORK, N. Y.

CLOSURE FOR COLLAPSIBLE TUBES, &c.

1,354,921.

Specification of Letters Patent.

Patented Oct. 5, 1920.

Application filed May 18, 1920. Serial No. 382,352.

To all whom it may concern:

Be it known that I, OSCAR SONDELM, a citizen of the United States, residing at 116 East Ninety-fifth street, in the city, county, 5 and State of New York, have invented certain new and useful Improvements in Closures for Collapsible Tubes, &c., of which the following is a specification.

My invention relates to closures for containers such as collapsible tubes, bottles, etc. and is particularly designed for use with receptacles containing liquid or semi-liquid material such as tooth paste, toilet preparations, etc., although it may also be used to 15 advantage in connection with receptacles containing powder or dry material.

My objects are to provide a closure which may be simply and inexpensively manufactured, which shall be sanitary at all times, 20 shall tightly seal the container when the latter is not in use and in which the cap or covering device shall be permanently secured to the container, or to the end closure member or portion of the same so that it 25 can not possibly be lost.

Devices have previously been proposed in which the end closure of a tube or bottle is provided with a neck having a side opening therein which is adapted to be covered and 30 uncovered by a cap permanently secured thereto. In such prior devices the cap has been mounted for rotation about the neck, either with a sliding movement or with a screw-threaded engagement therewith. It 35 has also been proposed to have the cap screw-threaded on the neck so as to move lengthwise thereof, when unscrewed, to uncover the side opening, a stop being provided to prevent the complete removal of 40 the cap from the neck.

None of these devices have, however, so far as I am aware, gone into extended commercial use, for various reasons. With all of them there is difficulty in maintaining an 45 effective seal at all times when the container is closed and at the same time providing a device which will always be clean and sanitary. If screw-threads are used, the same tend to become clogged with tooth paste or 50 other similar material and if a rotary move-

ment of the cap is made use of to close and open the orifice in the neck, for example, to align an opening in the cap with an opening in the neck, the movement tends to force material at the edge of the opening in the 55 neck, under the cap, when the latter is rotated into closing position. My invention overcomes these various difficulties in an exceedingly simple and practical manner by providing a neck having a side opening, 60 upon which neck the cap is mounted for sliding movement axially of the neck. The neck is given a smooth outer surface and the cap is provided with a friction and sealing member upon its inner surface, which slidably 65 engages the outer surface of the neck. Such a sealing and friction member may consist of a thin sheet of cork or plastic composition cork or the like retained against the inner side surfaces of the cap. Removal 70 of the cap from the neck is prevented by appropriate means, such as an upwardly extending pin at the top of the neck, this pin having an enlarged upper end against which the top of the cap may abut when 75 the cap is in fully opened position.

With such a device, the inner surface of the cap, of cork, or the like, engages the surface of the neck with sufficient friction to hold the cap in closed position or in open 80 position. The cork or similar material likewise provides an efficient sealing medium to tightly close the container when the cap is in a closed position. The cap with its lining, as described, is also adapted to keep the neck 85 clean at all times since when the cap is moved downwardly to close the orifice the lower edge of the cap and the sealing member carried thereby will clean the surface of the neck and sweep any paste or other mate- 90 rial which may be adhering to the edges of the opening downwardly, on to the upper surface of the end closure, which is preferably tapered, it thus being impossible for any such paste or material to be forced under the surface of the cap. Such removal of paste or the like containing a volatile ingredient also prevents the hardening of this material at the opening, such hardened material causing waste as its removal (as by 100

violently squeezing a collapsible tube) is followed by a rush of fresh paste through the opening.

In order that a clearer understanding of my invention may be had, attention is hereby directed to the accompanying drawings forming part of this application and illustrating one embodiment of my invention. In the drawings Figure 1 represents a partial side elevation of a container embodying my invention, the cap being shown in its upper or open position and Fig. 2 is a similar view with the cap in its lower or closed position, the cap and its contained sealing member being shown in position.

Referring to the drawings, container 1 may be a collapsible tube formed integral with the end closure 2, or the end closure may be a separate member secured to the 20 container 1, or the container 1 may be a rigid bottle or other form of non-collapsible container to which the end closure 2 is secured in any desired manner. The end closure 2 is preferably formed with a surface 25 which slopes downwardly and outwardly at all points, as shown.

The neck 3 extends upwardly from the end closure member 2, preferably axially thereof and may be integral with the closure 2 or secured thereto in any desired manner. The neck is provided with a side opening 4 which preferably takes the form of a slot extending lengthwise of the neck and of a sufficient length, in the case of a 35 container for tooth paste or the like to permit a stream of material of substantial width to be forced therefrom. The lower edge of slot 4 is preferably formed slightly above the lower end of neck 3.

40 Neck 3 is closed at its upper end as shown at 5 and from this top surface 5 of the neck a pin 6 preferably extends upwardly for a distance which may be slightly greater than the length of the slot 4. This pin is 45 upset at its upper end, or otherwise provided with an enlargement as is indicated at 7.

The cap 8 is formed of suitable metal, with a side portion which is preferably 50 cylindrical, or adapted to be slidably engaged with neck 3. The cap may also have a top portion 9 provided with a central opening through which the pin 6 slidably extends. The cap is preferably knurled 55 or roughened, as shown at 10, to facilitate manipulation of the same, it being sufficient to provide this nurling adjacent the upper edge of the cap only.

The sealing and friction material 11 preferably takes the form of a thin cylinder of cork mounted within the cylindrical side wall of the cap. Other material having sealing and friction properties, such as cork composition, may however be used. This 65 sealing member moves up and down with

the cap. The upper edge of the sealing member bears against the under surface of the top portion of the cap while the lower edge of the sealing member is preferably retained by pressing the lower edge of the 70 cylindrical portion of the metal cap inwardly, as is shown at 12.

The operation of the device will be apparent. When the cap is in its closed position shown in Fig. 2 the friction member 75 of cork or similar material 11 upon the smooth neck 3 will be sufficient to hold the cap securely in its closed position while at the same time the pressure of the sealing material upon the surface of the neck adjacent to the opening 4, will effectively seal the opening and prevent any leakage or evaporation of solvent in the paste therefrom. The neck 3 may be cylindrical, or may taper very slightly so that its bottom 85 diameter is very slightly greater than its top diameter, if desired. When the device is to be used the cap is pushed upwardly until its upper surface abuts against the stop 7 to uncover the opening, in which 90 position the cap will be held by friction. When the cap is pushed downwardly again toward the closing position the lower edge 12 of the cap, together with the lower edge of the cork cylinder 11, will push before it 95 any paste or other material contained within the tube, which may be sticking to the edge of the opening 4. This material is pushed away from the opening on to the sloping surface of the closure member 2 100 from which it may be readily wiped, it thus being apparent that none of this material may be forced into the interior of the cap.

What I claim is:

1. In a container, the combination of an 105 end closure portion having an upwardly-extending neck with a side opening therethrough and a smooth outer surface, a cap having an imperforate sleeve portion mounted on said neck to slide vertically thereon, to cover and uncover said opening, said cap carrying a tubular cork lining adapted to 110 slidably engage said neck and cover said opening when said cap is in covering position, and means to prevent the removal 115 of said cap from said neck.

2. In a container, the combination of an end closure portion having an upwardly-extending neck with a side opening therethrough and a smooth outer surface, a 120 cap having an imperforate sleeve portion mounted on said neck to slide vertically thereon, to cover and uncover said opening, said cap carrying a tubular lining of material adapted to exert friction against said 125 neck and to seal said opening when said cap is in covering position, and said neck having a pin extending upwardly from its upper end, with an enlarged upper end, said cap having a top portion through which 130

said pin slidably extends, adapted to abut against said enlarged end when said cap is in uncovering position.

3. In a container, the combination of an end closure portion having a sloping surface and an upwardly-extending neck with a side opening therethrough and a smooth outer surface, a cap mounted on said neck to slide vertically thereon to cover and un-
10 cover said opening, said cap having a top portion and an imperforate cylindrical portion with its lower edge bent slightly in-

wardly, a tubular lining of sealing and friction material within said cylindrical portion, extending from said top portion to 15 said lower edge, and means to prevent the removal of said cap from said neck.

This specification signed and witnessed this 10th day of May, 1920.

OSCAR SONDELM.
